DESIGN.

S. W. JOHNSON.
A PRINTED FABRIC.

No. 19,564.

Patented Jan. 7, 1890.

UNITED STATES PATENT OFFICE.

SETH W. JOHNSON, OF NEW YORK, N. Y.

DESIGN FOR A PRINTED FABRIC.

SPECIFICATION forming part of Design No. 19,564, dated January 7, 1890.

Application filed December 10, 1889. Serial No. 333,283. Term of patent 3½ years.

To all whom it may concern:

Be it known that I, SETH W. JOHNSON, a citizen of the United States, residing at the city, county, and State of New York, have 5 invented and produced a new and original Design for Printed Cotton and Woolen Cloths, of which the following is a specification, reference being had to the accompanying representation, forming part thereof, in which I 10 have represented my design by a photograph showing a face view of a piece of fabric.

The leading feature of my design is the ranges of dots forming scroll configurations with lateral curved vanes approximating ostrich-feathers.

15 *a* is the central part of the figure. *b* are the curved scroll-lines of dots diverging at

one side, and *c* are the curved scroll-lines of dots diverging at the other side, as represented. These figures, as will be seen in the 20 photographic view, are in lines or ranges and alternate in position.

What I claim is—

The design for printed cotton and woolen cloths herein shown and described, the same 25 comprising the scroll-shaped ranges of dots, substantially as set forth.

Signed by me this 6th day of December, A. D. 1889.

SETH W. JOHNSON.

Witnesses:

GEO. W. DELANO,
PETER Q. ECKERSON.
